UNITED STATES PATENT OFFICE.

ALFRED J. DION, OF INDIAN ORCHARD, MASSACHUSETTS.

AUTOMATIC SIGNAL INDICATOR FOR CREELING FRAMES.

Application filed May 7, 1925. Serial No. 28,664.

This invention relates to improvements in alarms and indicators for use in connection with creels, and it consists of the novel construction, combination and arrangement 5 of parts hereinafter fully described and claimed, and illustrated in the accompanying drawings, wherein:

Figure 1 is an elevational view illustrating the application of the alarm and indicator, 10 Figure 2 is a top plan view of the alarm and indicator with the top of the casing thereof removed,

Figure 3 is a view in front elevation of the alarm and indicator with the front of 15 the casing removed,

Figure 4 is a vertical sectional view taken on the plane indicated by the line 4—4 of Figure 2,

Figure 5 is a horizontal sectional view 20 taken on the plane indicated by the line 5—5 of Figure 3,

Figure 6 is a detail perspective view of one of the circuit closing and indicating plates of the device,

Figure 7 is a detail sectional view taken 25 on the plane indicated by the line 7—7 of Figure 3, and

Figure 8 is a similar view taken on the plane indicated by the line 8—8 of Figure 3.

Corresponding and like parts are referred 30 to in the following description, and designated in the several views of the accompanying drawings, by similar reference characters.

In the drawings 2 designates the rods, 35 the bobbin supports, 4 the bobbins, and 5 and 6 the thread guides of a creel. The threads 7 first pass through the guides 5, then through the guide 6, and thence through 40 the alarm and indicator 8 which is supported directly below the guide 6 by a bar or arm 8^a.

The alarm and indicator 8 comprises a casing which is fully open at its lower end 45 and embodies a front 9, back 10, top 11 and sides 12. The front 9 is removably secured in place by screws 13, and is together with the back 10 provided with vertical rows 50 of openings 14 through which the threads 7 pass. The openings 14 of the respective rows are equally spaced, and the respective rows of openings in the front 9 and back 10 are in alinement. In their inner sides the front 9 and back 10 are provided with 55 vertical grooves 15 which are arranged in alinement with the rows of openings 14.

and slidably receive the ends of horizontal tubes 16 carried by plates 17. The plates 17 are mounted in the casing for a limited vertical movement with respect thereto and 60 are supported in their uppermost position by the threads 7 which pass through the tubes 16. The plates 17 have vertically elongated openings 18 and are provided with ears 19 which extend into the openings 18 65 and to which the tubes 16 are secured. The plates 17 are arranged in relatively spaced units and the plates of each unit are relatively spaced so as to prevent one from interfering with the vertical movement of the 70 other. The openings 18 of the plates 17 of each unit are in registration, and the tubes 16 of the plates of each unit pass through said openings. The ears 19 of the respective plates 17 of each unit are so arranged 75 relatively as to prevent the tubes 16 from contacting with each other during the movement of one or more plates of a unit. At its lower end each plate 17 is provided with a number 20 corresponding to the number 80 of the bobbin the thread from which passes through its tube 16. Should a thread break the plate 17 carrying the tube 16 through which such thread passes will move 85 downwardly carrying the number thereon below the lower end of the alarm and indicator as illustrated in Figure 1. The tubes 16 and plates 17 are preferably made of brass.

Laterally beyond the slots 15 the front 90 9 and back 10 are provided with vertical slots 21 which slidably receive the edges 95 of vertical bars 22 which are made of hard rubber or other suitable insulating material. Horizontal disposed metal rods 23 are secured at their ends to the bars 22 and are arranged on opposite sides of the units of plates 17, a pair of the rods 23 being located below each horizontal row of tubes 16. The bars 22 are supported within the casing by 100 lugs 24 resting upon the lower sides of cams 25 fixed to and depending from a horizontal shaft 26. The shaft 26 is journaled in the sides 12 and is provided at one end with a hand lever 27. The rods 23 are in the path 105 of the tubes 16 and constitute stops for limiting the downward movement of any plate 17 released by the breaking of the thread 7 passing through the tube 16 thereof. The bars 22, lugs 24, cams 25, shaft 26 and hand 110 crank 27 provide means for resetting or returning the released plate 17 to its normal

position in order to permit the mended thread to be passed through the tube 16 thereof.

The alarm mechanism of the device comprises an electrically operated bell 28, stationary contacts 29 and 30 secured to the casing, a storage battery 31 or other suitable source of electrical energy, a lead 31^a extending from the bell 28 to the contact 29, a lead 32 extending from the bell to the battery 31, and a lead 33 extending from the battery to the contact 30. Conductors 34 are embedded in grooves 34^a in the outer side of one of the bars 22 and are secured in place by the rods 23. At their lower ends the conductors 34 are provided with contacts 35 and 36 which normally rest upon the contacts 29 and 30, respectively. As the tubes 16, plates 17 and rods 23 are made of metal, the bell circuit will be closed when the tube 16 of any one of the plates 17 is in contact with a pair of the rods 23.

The threads 7 will normally support the plates 17 in raised position. When the plates 17 are in this position the tubes 16 are in alinement with horizontally alined pairs of the openings 14 and out of contact with the rods 23 and the numeral bearing lower ends of the plates are housed within the casing. Should any one of the threads 7 break the plate 17 associated with such thread will be released and moved downwardly with the result that its numeral bearing lower end will be extended below the casing and its tube 16 brought into contact with two of the rods 23. It will thus be seen that when a thread breaks the alarm will be sounded and a numeral presented to view by which the bobbin from which the broken thread extends may be identified. The released plate 17 can be returned to and held in normal position until the repaired thread has been passed through its tube 16 by rocking the shaft 26 by means of the hand crank 27. The rocking of the shaft 26 will through the medium of the cams 25 and lugs 24, raise the bars 22 and rods 23 and the rods 23 will in turn raise the lowered plate 17. After the repaired thread has been passed through the tube 16, the shaft 26 is again rocked to move the cams 25 into their normal depending position and permit the rods 23 to return to their normal position. When in normal position the rods are spaced downwardly from the tubes 16 so as to permit the plates 17 to be solely supported by the threads 7. The alarm and indicator may be used in connection with any creel but it is especially adapted for use in connection with the creels of machines for making fabric and cord tires.

From the foregoing description, taken in connection with the accompanying drawings, the advantages of the construction and of the method of operation of the invention

will be readily apparent to those skilled in the art to which it appertains. While I have described the principle of operation of the invention, together with the device which I now consider to be the best embodiment thereof, I desire to have it understood that the device shown is merely illustrative, and that such changes may be made when desired as are within the scope of the invention as claimed.

What is claimed is:—

1. A device of the character set forth, comprising a casing provided with openings in the opposite sides thereof, vertical plates slidably arranged within the casing and provided with tubes, vertical bars slidably mounted within the casing, rods carried by the bars, means for movably supporting the bars and rods, said means comprising lugs secured to the bars, a shaft journaled in the casing, cams secured to the shaft and contacting with the lugs, and a lever connected to the shaft.

2. A device of the character set forth, comprising a casing provided with thread receiving openings in opposite sides thereof, vertical plates slidably mounted in the casing and provided with thread receiving tubes, said plates and tubes being made of metal, vertical bars of insulating material slidably mounted within the casing, metal rods carried by the bars, conductors secured to one of the bars and connected to the rods, an electrically operated alarm, contacts carried by the casing, a circuit for the alarm including said contacts, contacts carried by the conductors and normally having a circuit closing arrangement with respect to said first named contacts, and means for movably supporting the bars and rods.

3. An indicator for a creel comprising, in combination with the bobbins of the creel, a plate for and identifying each bobbin and provided with a slot, tubes carried by the plates for the reception of the bobbin threads, the tube of each plate passing freely through the slots of the other, and a casing in which the plates are mounted one in rear of the other to permit them to be supported therein by the threads and to permit them to move into projected position with respect thereto when released by the breaking of the threads.

4. An indicator for a creel comprising, in combination with the bobbins of the creel, a plate for and identifying each bobbin and provided with a slot, tubes carried by the plates for the reception of the bobbin threads, the tube of each plate passing freely through the slots of the other, a casing in which the plates are mounted one in rear of the other to permit them to be supported therein by the threads and to permit them to move into projected position with respect thereto when released by the breaking of the threads, and

means mounted in the casing and adapted to coact with the tube of a released plate to permit such plate to be retuned to and held within the casing while the thread is being again passed therethrough.

5. An indicator for a creel comprising, in combination with the bobbins of the creel, a plate for and identifying each bobbin and provided with a slot, tubes carried by the 10 plates for the reception of the bobbin threads, the tube of each plate passing freely through the slots of the other, a casing in which the plates are mounted one in rear of the other to permit them to be supported 15 therein by the threads and to permit them to move into projected position with respect thereto when released by the breaking of the threads, means mounted in the casing and adapted to coact with the 20 tube of the released plate to permit such plate to be returned to and held within the casing while the thread is being again passed therethrough, an electrically operated alarm, and a circuit for the alarm including 25 said last named means and adapted to be closed by the tube of a released plate contacting with said last named means.

6. An indicator for a creel comprising, in combination with the bobbins of the creel, 30 a plate for and identifying each bobbin and provided with a slot, tubes carried by the plates for the reception of the bobbin threads, the tube of each plate passing freely through the slots of the other, a casing in 35 which the plates are mounted one in rear of the other to permit them to be supported therein by the threads and to permit them to move into projected position with respect thereto when released by the breaking of the 40 threads, means movably mounted in the casing and embodying members spaced from the tubes, the tube of a released plate being adapted to contact with certain of the members of said last named means, and means for operating said last named means to return a released plate to and hold it within the casing while the thread is being again 45 passed therethrough.

7. An indicator for a creel comprising, in 50 combination with the bobbins of the creel, a casing provided in opposite sides thereof with vertical rows of openings and provided in the inner faces of said sides with vertical grooves, a plate for and identifying each 55 bobbin and provided with a vertical slot, vertically spaced tubes carried by the plates and having their ends positioned in said

grooves of the casing, the tube of each plate passing freely through the slots of the other, the bobbin threads passing through said 60 openings of the casing and said tubes to support the plates within the casing until broken, and means for limiting the movement of a released plate with respect to the casing.

8. An indicator for a creel comprising, in 65 combination with the bobbins of the creel, a casing provided in opposite sides thereof with vertical rows of openings and in the inner faces of said sides with vertical grooves, a plate for and identifying each 70 bobbin and provided with a vertical slot, vertically spaced tubes carried by the plates and having their ends positioned in said 75 grooves of the casing to slidably mount the plates within the casing, the tube of each plate passing freely through the slots of the other, the bobbin threads passing through said openings of the casing and said tubes to support the plates within the casing, vertical 80 bars slidably mounted in the casing, rods carried by the bars and positioned below the tubes, and bar actuating means.

9. An indicator for a creel comprising, in 85 combination with the bobbins of the creel, a casing provided in opposite sides thereof with registering openings through which the bobbin threads pass, said sides of the casing being provided with vertical grooves, members corresponding in number to the bobbins and located within the casing, and 90 tubes carried by the members and having their ends positioned in said grooves to slidably mount the members within the casing, the bobbin threads passing through the 95 tubes to support the members in raised position within the casing.

10. An indicator for a creel comprising, in combination with the bobbins of the creel, a casing provided in opposite sides thereof with registering openings through which 100 the bobbin threads pass, members corresponding in number to the bobbins and slidably mounted in the casing, tubes carried by the members and through which the bobbin threads pass to support the members in 105 raised position within the casing, and means carried by the casing and adapted to co-operate with the tube of a released member to return the member to and hold it in raised position while the thread is being again 110 passed through the tube thereof.

In testimony whereof I affix my signature.

ALFRED J. DION.
